UNITED STATES PATENT OFFICE

130,732

DESIGN FOR A SPOON OR OTHER ARTICLE OF FLATWARE

James Russell Price, Cranston, R. I., assignor to
The Alvin Corporation, Providence, R. I., a corporation of New York

Application June 17, 1941, Serial No. 101,497

Term of patent 14 years

To all whom it may concern:

Be it known that I, James Russell Price, a citizen of the United States of America, residing at 2325 Cranston Street, Cranston, Rhode Island, have invented a new, original, and ornamental Design for a Spoon or Other Article of Flatware, of which the following is a specification, reference being had to the accompanying drawing, forming part thereof.

Figure 1 is a front elevation of a spoon or other article of flatware showing my new design;

Figure 2 is a side elevation of the same;
Figure 3 is a reverse view of the same spoon or other article of flatware; while

Figures 4 and 5 are cross-sections of the spoon or other article of flatware of Figure 1 as taken on lines 4—4 and 5—5.

I claim:

The ornamental design for a spoon or other article of flatware, substantially as shown.

JAMES RUSSELL PRICE.
